DICTATING MACHINE

William F. Feyrer, Norwalk, Conn., assignor to
Dictaphone Corporation, New York, N. Y., a
corporation of New York

Original application March 25, 1931, Serial No.
525,172, now Patent No. 2,152,585, dated March
28, 1939. Divided and this application Febru-
ary 23, 1939, Serial No. 257,882

6 Claims. (Cl. 179—100.41)

This invention relates to phonographs and more particularly to translation devices adapted alternately to record and reproduce sound vibrations.

In devices of this nature recording and reproducing styli are frequently operatively connected to a vibratory member adapted to transmit vibrations either for recording or reproducing, control means being provided for bringing the styli selectively into engagement with the sound record tablet. When such control means is actuated the active stylus is raised from the tablet and the inactive stylus is lowered upon the tablet. It is well known that such a vibratory system must be damped to minimize distortion in recording and reproducing sound waves, and for other reasons as will appear hereinafter. It is also a recognized fact in the art that it is desirable to provide a different degree of damping when recording than when the device is used for reproducing.

It is therefore an object of this invention to provide simple and practical means for automatically varying the degree of damping imposed upon the system when shift is made to condition the device for recording, and vice versa.

A further object is to provide simple, practical and efficient means for damping a vibratory member of the nature described and for selectively adjusting the degree of damping imposed upon such member under varying operating conditions.

Other objects will be in part obvious and in part pointed out hereinafter.

The invention accordingly consists in the features of construction, combinations of elements and arrangements of parts as will be exemplified in the structure to be hereinafter described and the scope of the application of which will be indicated in the following claims.

In the accompanying drawings, in which are shown one or more of the various possible embodiments of this invention, being a division of an application filed by me on March 25, 1931, Serial No. 525,172, now Patent No. 2,152,585, dated March 28, 1939.

Fig. 1 is a top plan view of a combination electromagnetic recorder and reproducer, or vibration translation unit, made in accordance with the present invention, the cover being cut away as indicated on line 1 in Fig. 2;

Fig. 2 is a rear elevation of the electric translation unit shown in Fig. 1 and shows also the upper part of the carriage of the phonograph;

Fig. 3 is a side elevation thereof partly in section on line 3 of Figs. 1 and 2;

Fig. 4 is a view similar to Fig. 1, but shows certain modifications and additions;

Fig. 5 is a view similar to Fig. 2, but shows the modifications as in Fig. 4;

Fig. 6 is a cross-section and side elevation taken one line 6 of Figs. 4 and 5; and

Fig. 7 is a view similar to Fig. 6, but with parts 5 omitted and with other parts shown in section substantially on line 7 of Figs. 4 and 5.

Referring to the drawings, an electromagnetic translation unit, indicated generally by the reference 22, is shown mounted upon a carriage 21 provided with slides 163, 164 and 165 adapted to be moved in a manner fully described in my above mentioned application, to shift a pair of weight levers 135 and 136 into and out of operative relation to a record cylinder 15 when said slides are actuated by the appropriate shifting of a state control lever 159, pivotally mounted upon the carriage, to condition the translation unit for recording, reproducing, or to be inoperative. In the present embodiment of the invention the combined recorder and reproducer mechanism, which I have chosen to call a vibration translation unit, is electromagnetically operated, as will hereinafter appear. In this unit a vibratory armature is connected to transmit vibrations to or from suitable styli, in the one case to produce a record upon the record cylinder, and in the other to reproduce dictation or other matter previously recorded. For a better understanding of this translation unit, reference is made to the drawings which show the vibratory armature at 130, connected by means of wires or rods 246 and 247 capable of transmitting vibration, to a pair of small levers or stylus carriers numbered respectively 131 and 132. Carrier 131 is provided with a recording stylus 133, while carrier 132 is provided with a reproducing stylus 134. Each of these carriers is pivotally mounted, as shown, near the upper end of a weight lever numbered respectively 135 for the recording stylus and 136 for the reproducing 40 stylus.

The carriage frame 21 is provided with two upwardly extending standards 137 and 138 disposed in alignment near the rear upper edge of the frame. A short shaft 142 is adjustably supported 45 by said standards for rotational movement, and tightly mounted upon the left end of this shaft, as viewed in Fig. 2, is the recorder weight lever 135. As thus mounted the recorder weight lever is free to oscillate in a vertical plane toward and away 50 from the record cylinder, but is incapable of lateral movement. On the other hand, the reproducer weight lever 136 is mounted upon the shaft 142 in such a way as not only to be capable of rocking to and from the record cylinder, but 55

also to rock to a limited extent in a lateral direction, namely longitudinally of the shaft 142. This is accomplished by providing the weight lever 136 with a relatively long hub 143, which has 5 a bore constricted at its center to a relatively tight fit on the shaft 142 but flaring out toward each end of the hub, as illustrated at 144. This permits a limited lateral movement of the stylus carrier of the reproducing stylus in order that the 10 stylus may accurately track the record while reproducing.

Lever 135 has at its lower end a suitably shaped abutment 146, and the reproducing lever 136 has at its lower end a suitably shaped abutment 147. 15 Abutment 146 is adapted to cooperate with slide 164 and abutment 147 with slide 165 which slides, as stated above, are movable in the carriage to swing the styli away from the record or to permit their return to the record surface by swinging 20 the weight levers about their common axis 142. The weight levers are so proportioned that, while it is necessary to push their lower ends rearwardly to raise the styli from the record cylinder, they will swing in the other direction 25 to permit return of the styli to the record cylinder under their own weight, when the slides cooperating with the abutment ends thereof permit. It may be mentioned that in the preferred operation of applicant's translation unit the recording stylus is normally biased to a position where it engages the record cylinder and the reproducing stylus to a position where it is not in engagement with the record cylinder.

The recorder-reproducer translation unit is 30 mounted upon the carriage frame in such a manner that adverse vibration and noises are absorbed before reaching the metallic part of the mechanism, and for this purpose a rubber plate 230 is fastened to the bottom of the permanent magnet 231 by means of screws 232, and this assembly is in turn fastened to the top of the carriage frame by three screws 233, which threadedly engage carriage bosses 234 and 188.

The magnet core 231 is formed substantially 35 U-shaped, with the central portion 236 raised above and offset from the plane of the legs 239 and 240 which extend rearwardly toward the back of the unit. Upon this offset portion 236 there is mounted a magnet coil 237 connected in 40 the speaking circuit of the phonograph in any usual or desired manner. The magnet is provided with an armature 130 pivoted by means of a pin 238 to one pole piece 239 of the magnet and extending horizontally across the space between 45 them to a point adjacent the end of the other pole piece 240 of the magnet. The armature 130 is provided adjacent the pole piece 240 with a comparatively stiff flat spring 241 secured to the armature by means of a screw 242. Two plates 50 243 and 244, of substantially L-shaped construction, are secured adjustably along the side of the pole piece 240 by means of a screw 245. A portion of each of these members is positioned in 55 spaced relation to the spring 241, one upon one side, and one upon the other side thereof, as shown in Figs. 1 and 4, and serves to support between itself and the spring 241 a short section of rubber tubing or other resilient material suitable for damping vibrations of the armature. As 60 the two plates are adjustably mounted they may be moved toward or away from the resilient member 241 in order to determine the extent of the air gap existing between the armature and the pole piece 240.

75 This arrangement enables the recorder and

reproducer to operate either with strong or weak voice currents, and, also, this adjustment makes controllable the degree of compression under which the rubber tubing is placed so as to determine the degree of damping. If the machine 10 is to be used by a dictator having a weak, or non-resonant, voice, the gap should be relatively small, while on the other hand, if the voice of the dictator is strong, the gap should be relatively large. And, further, it should be understood that by increasing the compression upon the rubber tubes, the recording will be high pitched, while by decreasing the compression low pitched recording may be had.

The stylus carriers 131 and 132 are connected 15 to the armature by suitable wires or other means 246 and 247 in such a way as to enable the recording stylus, when it is in contact with the record cylinder, to respond to vibrations caused by voice currents acting upon the magnet and 20 produce a mechanical record upon the record cylinder of the sound which has produced these currents. When the recorder weight lever is thrown back by movement of the slide 164 so as to raise the recording stylus from the record, the 25 carrier 131 swings around its pivot and changes its position so that it is possible to employ a fixed length of wire to connect the said carrier with the armature. This also applies to the reproducing stylus which is adapted to track a 30 record groove, transmit the vibrations therefrom through the wire 247 to the armature, producing vibration of the armature and changes in the reluctance of the magnetic circuit of the magnet. These changes in reluctance produce correspond- 35 ing current changes in the speaking circuit to produce sound vibrations through the medium of any suitable loud speaker device, not shown, said vibrations corresponding with the sound vibrations originally recorded. A casing or cover 248 40 extends over the entire recording and reproducing unit and is secured to the sides of the carriage block by means of screws 340.

The unit just described, more particularly with reference to Figs. 1, 2 and 3, does not include 45 in its unit assembly the stylus weight levers 135 and 136, for these, as has been explained above, are mounted upon a shaft which is supported within bosses 137 and 138 of the carriage block. Figs. 4, 5, 6 and 7 show a modified construction 50 in which the weight levers 135 and 136 are mounted upon centers which are carried by a bracket member 249 comprising a plate portion 250 extending across the magnet pole pieces and secured thereto by means of screws 251 and 252, 55 and to forwardly and downwardly extending bracket arms 253 and 254 for supporting the adjustable centers 139 and 140. This construction, by removing the support of the stylus levers completely from the metallic body of the carriage and mounting these levers upon the magnet itself, which is resiliently supported by the carriage, provides an additional safeguard against the transmission of metallic and mechanical noises to the styli; and provides a self-contained 60 recording and reproducing unit including weight arms and stylus carriers, readily attachable to and removable from the carriage.

In connection with the modified form there are shown other important features, and it is to be 70 understood that these features may be incorporated, if desired, in the type of reproducer and recorder unit shown in Figs. 1 to 3. One of these features constitutes a device by means of which the rate at which the weight levers descend, when 75

they are permitted to do so by the forward movement of their respective operating slides, may be controlled, and comprises a dash pot 255 mounted above the magnet, in this case as an integral part 5 of the bracket member 250. This dash pot is fastened substantially above the reproducer slide 165. Mounted to reciprocate within the dash pot is a plunger 256 having a pin 257 extending transversely across its rear end. A lever 258 is 10 pivotally mounted upon a bushing member 145 which surrounds the center 139 and at its upper end is slotted to embrace the pin 257, while at its lower end it is slotted to embrace a pin 259 extending horizontally from a portion of the left 15 side wall of the reproducer slide 165.

The operation of this mechanism will be readily understood when it is remembered that the reproducer slide really actuates the stylus weight lever only during its movement toward the rear 20 of the carriage, that is, when it raises the stylus from the record. When the reproducer slide moves toward the front of the carriage, the reproducer weight lever moves by gravity and unless its movement is retarded the stylus may descend upon the record cylinder with such impact 25 as to cause considerable shock to the sensitive stylus and to cause a sharp clicking noise annoying to the operator. Although the dash pot is connected directly with the reproducer slide it 30 will be understood that it will have the same effect upon the recorder slide because the latter is so related to the reproducer slide as always to move with the reproducer slide simultaneously in the opposite direction thereto. The means by 35 which this simultaneous action of the two slides occurs is fully described in the parent application to which reference is made for further details. In effect, the dash pot retards the movement of the stylus weight levers in either direction, for 40 in one case it retards their gravitational movement and in the other case it retards the action of resilient means, not shown, employed normally to bias the recorder slide to operative position.

Provision is further made for controlling the 45 damping of the armature so as to produce relatively heavy damping during the recording operation and relatively light damping during the reproducing operation. The ability to change the armature from a slightly damped condition for 50 reproducing to a highly damped condition for recording and vice versa, is highly desirable because vibrations received from the reproducing stylus are less strong than the vibrations imparted to the armature by the voice currents during dictation. This device comprises a stud or 55 pin 260 (see Fig. 1 and Figs. 4, 5, 6 and 7) to which pin is pivotally mounted an auxiliary damping arm 261, the lower end of which is pivotally mounted by means of a pin-and-slot connection 60 to the pin 259 of the reproducer slide, the same pin to which the dash pot lever is attached. Adjacent the upper end of the arm 261 there is supported a small block of felt or rubber 262 which 65 may be so designed in thickness as to be adapted to move into contact with the magnet armature 130. With this arrangement of parts, when the reproducer slide is in its rearward position, that is, while the machine is conditioned for recording, the damping block 262 will be brought into relatively 70 firm contact with the armature 130, while, when the reproducer slide is moved forwardly of the carriage to bring the reproducing stylus into engagement with the record, the damping block 262 will be partially or entirely removed from 75 contact with the armature, so that the damping

effect will be proportionately lightened or completely removed.

Referring to the drawings, it will be seen that a flat surface is provided at the extreme top end 5 of each of the stylus weight carriers, upon which flat surface appears an indication to enable the operator to determine which stylus is in operative relation to the record by merely glancing down at the machine. The indications shown upon these surfaces, indicated by the numerals 10 263 and 264, will only appear beyond the rear edge of the cover 248 when the respective weight carriers are in their rearward position and their respective styli are operatively engaging the record. This will be clear by reference to Fig. 6 15 263 and 264, will only appear beyond the rear edge of the cover 248 when the respective weight carriers are in their rearward position and their respective styli are operatively engaging the record. This will be clear by reference to Fig. 6 15

wherein the indication on the surface 263 of the reproducer weight carrier is visible, while the surface 264 of the recorder weight lever is hidden from view.

As many possible embodiments may be made 20 of the above invention without departing from the scope thereof, it is to be understood that all matter herein set forth or shown in the accompanying drawings is to be interpreted as illustrative and not in a limiting sense. 25

I claim:

1. In a dictating machine, in combination, a vibratory armature, a stylus movably mounted adjacent said armature, means for moving said stylus into respectively operative and inoperative positions, and means responsive to movement of said stylus into operative position for damping the vibratory movement of said armature. 30

2. In a dictating machine, in combination, a vibratory armature, recording and reproducing styli movably mounted adjacent and connected with said armature, means for moving said reproducing stylus from an operative position to an inoperative position, and simultaneously moving 40 said recording stylus into an operative position, and means responsive to said operation of said stylus moving means for damping the vibratory movement of said armature.

3. In a dictating machine, in combination, a vibratory armature, recording and reproducing styli movably mounted adjacent and connected with said armature, means for moving said reproducing stylus from an operative position to an inoperative position, and simultaneously moving 50 said recording stylus into an operative position, and damping means for said armature responsive to said operation of said stylus moving means for increasing the damping effect of said damping means. 55

4. In a dictating machine, in combination, a vibratory armature, a pair of styli mounted for independent movement adjacent said armature, independent means for transmitting vibrations between said armature and each of said styli, 60 means for moving one of said styli from an operative to an inoperative position and simultaneously moving said other stylus to an operative position, and means for controlling the rate of change of said styli from one position to another. 65

5. In a dictating machine, in combination, a vibratory armature, a pair of styli mounted for independent movement adjacent said armature, independent means for transmitting vibrations between said armature and each of said styli, 70 means for moving one of said styli from an operative to an inoperative position and simultaneously moving said other stylus to an operative position, and means for retarding the operation of said stylus moving means. 75

6. In a dictating machine, in combination, a carriage mounted adjacent a record support, recording and reproducing styli mounted on said carriage for movement toward and away from said record support, an electromagnetic translator mounted upon said carriage comprising a

vibratory armature, independent means for transmitting vibrations between said armature and said styli, and means on said carriage for selectively moving said styli toward said record support to an operative position.

WILLIAM F. FEYRER.
